UNITED STATES PATENT OFFICE.

GEORGE A. LLEWELLYN, OF NEW YORK, N. Y.

DESIGN FOR A FLORAL-BOUQUET HOLDER.

Application filed January 28, 1925. Serial No. 12,166. Term of patent $3\frac{1}{2}$ years.

To all whom it may concern:

Be it known that I, GEORGE A. LLEWELLYN, a subject of the King of Great Britain, residing at New York city, in the county of New York and State of New York, have invented a new, original, and ornamental Design for a Floral-Bouquet Holder, of which the following is a specification, reference being had to the accompanying drawing, forming part thereof.

In the drawing:—

The figure is a perspective view.

I claim:—

The ornamental design for a floral bouquet holder, as shown.

GEORGE A. LLEWELLYN.
